CLOSURE FOR CONTAINERS

Alex Limbach, Carmel, N. Y.

Application December 20, 1940, Serial No. 370,954

7 Claims. (Cl. 220—41)

This invention relates to closures for containers and more especially to a closure for an atomizer of the type disclosed in my co-pending application, Serial No. 298,012.

An object of this invention is a simple, efficient and inexpensive closure which provides a tight seal for the discharge opening of an atomizer or container.

In the atomizer disclosed in said application, Serial No. 298,012, an annular band completes the assembly of the component parts and is provided with an opening through which the atomized liquid is discharged. In the preferred embodiment of the present invention, the band is equipped with a slider which carries a strip of sealing material such, for example, as rubber. The structure of the slider is such that during movement of the slider to and from sealing position, the sealing material is maintained out of contact with the band but in sealing position the sealing material engages the band around the discharge opening to form a tight seal. With this arrangement, movement of the slider into and out of sealing position is not impeded by the drag which would be present with a structure having the sealing strip at all times in engagement with the band.

Other objects, novel features and advantages of this invention will become apparent from the following specification and accompanying drawing, wherein:

Fig. 1 is a side elevation partially broken away illustrating a preferred embodiment of the invention with the slider in sealing position;

Fig. 2 is a plan view of Fig. 1;

Fig. 3 is a perspective view of the slider;

Fig. 4 is a section substantially on the line 4—4 of Fig. 1;

Fig. 5 is a view similar to Fig. 4 with the slider out of sealing position;

Fig. 6 is a side elevation of a modification of the invention with the slider in sealing position;

Fig. 7 is a plan view partially broken away, and

Fig. 8 is a fragmentary view similar to Fig. 6 with the slider out of sealing position.

For illustrative purposes, this invention is disclosed as applied to the atomizer illustrated in said co-pending application, Serial No. 298,012. The atomizer structure consists in general of a bulb 11 together with component parts, which are attached by means of a band 12 to the neck 13 of a container 14. The band 12 is provided with a raised or offset portion 15 having a discharge opening 16 in alignment with the atom-

izing opening 17 corresponding to the aperture 13 in the cup member 10 illustrated in said application, Serial No. 298,012. A thin metal slider 18 is provided with a bottom flange 19 and a top flange 20 having arms 21. This slider is supported by the band 12 with the flange 19 and the arms 21 co-operating with surfaces on the band to hold the slider on the band for back and forth movement. A strip 22 of sealing material such, for example, as rubber, is arranged on the inner surface of the slider 18 and is held in place by end tabs 23 and 24 turned inwardly over the ends of the strip. The edge of the tab 23 is embedded in the sealing strip 22 while the inner end of the tab 24 is flush with the sealing material to provide an abutment, the purpose of which will later become apparent.

The slider 18 is movable between its sealing position illustrated in Fig. 4 and the position illustrated in Fig. 5. In its sealing position, the slider overlies the offset portion 15 with the sealing material engaging the surface of the offset portion to close tightly the opening 16. The end walls of the offset portion 15 form shoulders 25 and 26, one of which 25 as is clearly shown in Fig. 4 is engaged by the inner edge of the tab 24 to limit movement of the slider in one direction, thereby locating the slider in sealing position with the tab 23 resting on the band 12 and engaging the shoulder 26.

Upon movement of the slider 18 from the position shown in Fig. 4 to the position shown in Fig. 5, the rounded portion of the tab 23 rides up the shoulder 26 of the offset 15 and slides over the top of the offset with the tab 24 riding on the main surface of the band. After sufficient movement of the slider, the tab 23 moves out of engagement with the surface of the offset portion 15 and into engagement with the main portion of the band, the necessary amount of radial movement of the slider being permitted by reason of the resiliency of the flanges 19 and 20. Upon movement of the slider from the position shown in Fig. 5 to the position shown in Fig. 4, 45 the rounded portion of the tab 23 engages the shoulder 25 and is cammed outwardly sufficiently to ride on to the top surface of the portion 15 and such movement of the slider is continued until the abutment formed by the end of the tab 24 engages the shoulder 25. Due to the fact that the tabs 23 and 24 are turned inwardly over the ends of the rubber strip 22, the tabs ride on the band 12 and maintain the strip 22 out of contact with the band except when the slider is in the position shown in Fig. 4, thereby facilitating

movement of the slider into and out of sealing position by reason of metal to metal contact rather than rubber to metal contact, the latter producing considerably more friction than the former. The sealing material comes into contact with the outer face of the offset portion 15 only after the tab 23 rides down the shoulder 26 off the offset portion 15.

In the modification illustrated in Figs. 6, 7 and 8, the slider 28 is supported on the band 12 by the bottom flange 29 and arms 31 extending from a top flange 30. A strip of sealing material 32 is contained in a pocket 33 formed in the slider 28 and is held in place by suitable adhesive. In the slider is provided an offset portion 34 which cooperates with a nib 35 on the band 12 to locate the slider 28 in sealing position relative to the discharge opening 16 in the offset portion 15. The two elements 34 and 35 constitute means for locating the slider 24 in sealing position.

While I have shown this closure in relation with an atomizer, it will be readily understood that it may be adapted to any container having a similar curved band or portion thereof.

I claim:

1. A device of the character described comprising an annular band having shoulders and an offset portion containing an aperture, a slider having resilient flanges engaging said shoulders to slidably attach said slider to said band, a strip of sealing material engaging the inner surface of said slider, and a tab at each end of said slider extending inwardly over the ends and around the inner corners of said strip to attach it to said slider, said tabs engaging said band and serving to maintain said strip out of contact with said band except when said strip overlies said offset portion.

2. A device according to claim 1 in which the end of one tab is arranged to form an abutment to engage one end wall of said offset portion to locate the slider in sealing position.

3. A device of the character described comprising an annular band having shoulders and an apertured offset of less width than said band,

a slider having resilient means slidably attaching it to said band, a strip of sealing material engaging the inner surface of said slider, and a tab at each end of said slider extending inwardly over the ends and around the inner corners of said sealing material strip to attach it to the slider, said tabs engaging said band and serving to maintain said strip out of contact with said band except when said strip overlies said offset portion.

4. A device according to claim 3 in which the edge of one tab is arranged to constitute an abutment engageable with one end wall of said offset portion to locate said slider in sealing relation on said offset portion.

5. A closure for containers comprising a curved band having shoulders and an apertured raised portion, a slideable clip having resilient means for attaching it to said band, a strip of sealing material engaging the inner surface of said clip, and a tab at each end of said clip extending inwardly over the ends and around the inner corners of said sealing material strip to attach it to inner surface of said clip with the tabs engaging said band to maintain said strip out of contact with said band except when the strip overlies said raised portion.

6. A closure according to claim 5 in which the curved portion of said tabs form a smooth sliding surface against the curved band and the end of one tab is so arranged to provide a stop in the sealing position when contact is made with said tab against one end wall of the raised portion.

7. A device of the character described comprising an annular band having shoulders and an offset portion containing an aperture, a slider having resilient flanges engaging said shoulders to slidably attach said slider to said band, a pair of tabs extending inwardly from the slider into engagement with said band, and a strip of sealing material located between said tabs, said strip being of less thickness than the inward extent of said tabs, whereby said strip is maintained out of contact with said band except when said strip overlies said offset portion.

ALEX LIMBACH.
